DEVICE FOR REGULATING THE TEMPERATURE OF SUPERHEATED STEAM.

1,141,956.

Specification of Letters Patent. Patented June 8, 1915.

Application filed April 9, 1913. Serial No. 760,034.

To all whom it may concern:

Be it known that I, KARL GUTHARDT, a citizen of the German Empire, residing at Kiel-Hassee, Germany, have invented certain new and useful Improvements in Devices for Regulating the Temperature of Superheated Steam, of which the following is a specification.

This invention relates to steam boilers provided with superheaters and the subject matter is a device for regulating the temperature of the superheated steam.

Until lately, the temperature of the superheated steam was generally influenced by throttling dampers or disks built into the heating flues of the boiler. This course has however been abandoned of late, because such dampers are rapidly destroyed by the heating gases making disturbing and costly repairs necessary within a short time. As a consequence the method now followed is to overheat the steam to a higher temperature than the one at which it is used, and to cool it down to the desired temperature by for instance the introduction of water into the superheating pipes. As the heat utilized for superheating the steam is partly employed in a futile manner on account of the subsequent recooling, all such recooling-devices work with great loss of heat.

The object of the present invention is now to provide a device for regulating the temperature of the superheated steam which is devoid of these disadvantages.

For the purpose of regulating the temperature of the superheated steam in accordance with the present invention, means are provided which permit the part of the heating surface of the superheater, through which the boiler steam first runs, to entirely or partially be deprived of its principal object as steam superheater, by the injection of an adjustable quantity of water into the inner of the superheating pipes and to be utilized as an additional boiler heating surface for the generation of steam.

In the accompanying drawing, one embodiment of the invention is illustrated in connection with a tubular boiler with header, and Figure 1 shows diagrammatically a representation thereof as applied to a tubular boiler with header; Fig. 2 a portion of the superheater in side elevation, partly in section and in larger scale; Fig. 3 an end view of Fig. 2 seen from the right; and Fig. 4 a detail in still larger scale.

The tubular boiler with header, represented in Fig. 1, consists of a cylindrical upper boiler A and two water chambers B and C which are connected to each other by means of a nest of water tubes D. In the free space limited by the upper boiler A, the water chambers B and C and the tube nest D, the superheater is situated, and it consists of two systems of serpentine pipes M displaced relative to each other. These serpentine pipes open on the one hand into a steam chamber L of square cross section, and on the other hand into a similarly shaped steam exhaust chamber N. The first one of these steam chambers is connected with a steam conduit F leading from the fresh steam valve E, while the supply conduit W for the superheated steam is connected with the chamber N.

In accordance with the present invention, narrow pipes R, closed at their inner ends are inserted in the upper ends of the serpentine pipes M of the superheaters, which narrow pipes pass through the outer wall of the chamber L, secured by tightening plugs V. All of these inserted pipes R open into a wide distributing pipe K outside the chamber L, being connected thereto by pipe elbows P, and this distributing pipe K is connected with the water chamber of the upper boiler A by means of a pipe H and may be disconnected therefrom by means of a closing member G.

Helically wound plate strips S are pushed over the inserted pipes R and these strips rest on the one hand on the inserted pipes R and on the other hand on the inner wall of the serpentine pipes M. The inserted pipes R are moreover provided with a great number of small holes r^1 , which follow in a continuous line the winding of the plate strip, being arranged on both sides of this strip and along its whole length.

The operation of the described device is as follows: During the normal operation of the boiler the valve G is closed and the superheater generates steam of certain temperature corresponding to its normal operation. Should now for instance, on account of forced running, the temperature of the superheated steam reach above the desired heat, it will then be necessary only to open the valve G. Some of the boiler water will then enter through the conduit H into the distributing pipe K, which water subsequently will proceed from there to the indi-

vidual inserted pipes R, through the pipe elbows P. Though the holes r^1 water will thereupon be injected and subsequently evaporate against the wall of the serpentine superheater pipe M, which is being heated from the outside. The water that does not reach the walls will be thrown outwardly by the whirling steam following the helical plate strip, and will therefore also be evaporated. Since therefore much wet steam is produced in the part of the superheater into which water is injected, the lesser or greater opening of the valve G will consequently cause that part of the heating surface of the superheater which is next to the boiler to be partially or entirely diverted from its proper function, namely that of superheating the steam generated in the boiler, and the steam, running through the superheater which now is considerably shortened in its operative length, will leave the superheater at a lower temperature, than when the valve G is closed. The desired degree of superheat may therefore be adjusted within limits through the greater or smaller width of opening of the valve G. These limits may be made so wide that the superheater could also be utilized for increasing the output of the boiler when it is being started, or when only saturated steam is being used. In order to attain this the valve E has to be closed altogether, and the water valve G entirely open. As much water as can pass through the holes r^1 will then be admitted in the serpentine pipes M, to be evaporated there and taken out through the chamber N as well dried or somewhat superheated steam. This steam may thereupon be mixed with the boiler steam, either in the boiler or in the supply conduit. Instead of the boiler water, feed water or its equivalent may naturally be injected into the superheater.

The described device for regulating the temperature of the superheated steam, and which may be applied to all kinds of boiler systems, is distinguished by great simplicity. It will also be evident that with this regulating device, neither the entire arrangement of the boiler plant nor its accessibility suffer any inconvenient alteration. The superheater pipes M are in particular very accessible for taking out the inserted pipes R, and they may if necessary be rerolled. Furthermore the boiler water injected through the pipes R is transferred into useful steam within the superheating pipes, and no loss in

energy or heat will be experienced by the described device for regulating the temperature of the superheated steam, which for instance would unavoidably be the case by re-cooling the steam through injection of water in the superheating pipes.

I claim:

1. A device for regulating the temperature of superheated steam having a serpentine shaped conduit for the superheated steam comprising a steam entering chamber, a steam exhaust chamber and a plurality of horizontally disposed pipes joined by short bends connecting said two chambers; a sprinkler inserted in each of the horizontally disposed pipes which are situated nearest said entering chamber, a helical partition surrounding each of said sprinklers causing the passing steam to receive a whirling motion, each of said sprinklers being connected with the water chamber in the main boiler, and means for regulating the quantity of water entering said sprinklers.

2. A device for regulating the temperature of superheated steam having a serpentine shaped conduit for the superheated steam comprising a steam entering chamber, a steam exhaust chamber and a plurality of horizontally disposed pipes joined by short bends connecting said two chambers; a sprinkler inserted in each of the horizontally disposed pipes which are situated nearest said entering chamber, a helical partition surrounding each of said sprinklers causing the passing steam to receive a whirling motion, each of said sprinklers being connected with the water chamber in the main boiler, and hand operated means for regulating the quantity of water entering said sprinklers; said sprinklers being closed at their inner ends and provided with a plurality of holes arranged in two rows on either side of said helical partition and parallel thereto; whereby an adjustable quantity of water may be inserted into the first part of the horizontally disposed pipes which are situated nearest said entering chamber, thereby partly or wholly suppressing the superheating of the steam, said water being converted into useful steam.

In testimony whereof I have affixed my signature in presence of two witnesses.

KARL GUTHARDT.
